UNITED STATES PATENT OFFICE.

EDWARD BRUNHOFF, OF CINCINNATI, OHIO.

DISPLAY LID.

Application filed May 21, 1926. Serial No. 110,765.

My invention relates to improvements in display lid adapted to be applied to original containers during the period the contents thereof is being vended. One of its objects is 5 to provide a display lid adapted to be detachably applied in place of the original lid of the container, and having a hinged section adapted to lift upon its hinge to give convenient access to the interior of the container. 10 Another object is to provide a display lid having a hinged section and having a transparent section to display the goods while protecting the goods from dust and injury. Another object is to provide an improved means 15 to detachably mount the lid. Another object is to provide improved means and to construct and hinge the lid sections. My invention also comprises certain details of form and arrangement and combination of components, all of which will be fully set forth 20 in the accompanying drawings, in which;

Fig. 1 is a perspective view of a container with my improved display lid attached thereto.

Fig. 2 is a vertical sectional detail taken upon line 2—2 of Fig. 1.

Fig. 3 is a bottom plan of a portion of the lid shown in Figs. 1 and 2.

Fig. 4 is a sectional detail taken along the 30 axis of the hinge of Figs. 2 and 3 with one of the lid sections turned back upon its hinge to rest upon the top of the other lid section.

Fig. 5 is a perspective detail showing the means to hold the transparent members in 35 place.

Fig. 6 is a perspective view of a portion of the lid and the lid attaching means.

The accompanying drawings illustrate the preferred embodiment of my invention, in which 15 represents an original container, a candy pail or bucket for instance, from which the original wooden lid has been removed, and my improved display lid detachably attached thereto, to serve as a lid during the 40 period in which the contents of the container is being vended.

The display lid comprises two sections 16 and 17 hinged together by a continuous hinge along their meeting edges, and preferably either one thereof adapted to serve as a lid 45 to turn upon the hinge and thereby give ready access to the interior and contents of the container when in open position and to afford a protection to the contents of the container when in the closed position.

The hinge comprises two hinge leaves 19

and 20 connected together upon and by a hinge rod or axle 22 to form a continuous hinge from one side to the other of the lid. The ends of the hinge axle project at each 60 end beyond the hinge leaves, and is threaded at each end to receive the eye 24 of a lid attaching member and a nut 25. Each of the lid sections comprises a semi-circular sheet metal member 26 which forms a metal binding for the curved edge of one of the transparent panels 27, and is provided with a recess 28 to receive the curved edge of the panel 27 and a downwardly directed curved section 30 which enters along the upper end 70 of the inner face of the wall of the container 15 to form a practically dust proof joint with said container. The combined cross sectional pattern and curve of the sheet metal members 26 and 30 is such as to provide a 75 substantially rigid and relatively light frame structure to hold the transparent panel in place. The opposite ends of each frame 26 are rigidly brazed to opposite ends of one of the hinge leaves 19 or 20. The transparent 80 panels are not inserted until after the hinge leaves and frames are brazed together. After the transparent panels are inserted they are retained in place by means of short sections 32 which are formed by partially 85 severing the same from the ends of the members 26 and 30 and then bending the free ends of the sections 32 across in rear of the ends of the back or straight edges of the transparent panels to prevent retraction of the 90 transparent panels from the recesses 28 of the frames 26. The free ends of the sections 32 are then soldered to the inner face of one of the hinge leaves 19 or 20 by means of a 95 globule of solder 33 to prevent accidental displacement of the transparent panels. In the event that one of the transparent panels should become fractured, the solder globules could be heated to free the ends of sections 32, which could then be bent out of the path of the 100 transparent panel thus enabling the fractured panel to be removed and a new panel inserted and locked in position by again bending the free ends of sections 32 into position 105 and soldering them to the inner face of the hinge leaf.

In order to detachably attach the lid to the open mouth of a container 15 I provide attaching members held by eyes 24 to opposite ends of the hinge rod. Each attaching member preferably comprises a pair of resilient fingers 35 and 36 united by a yoke 37 at their 110

bers 40 and 41 are provided with projections 46 formed by bending over one corner thereof. The members 45 and 46 interengage to limit the pivotal movement of the rear brace 5 members relative to the front brace members to thereby hold the rear side rails and front side rails braced rigidly a predetermined distance apart when the stand is in extended position, as shown in Fig. 1, and to fold together 10 as shown in Fig. 2 when the stand is collapsed. The rear side rails are shorter than the front side rails, which causes the stand to support the articles to be vended in an inclined position best adapted to be observed 15 from in front of the stand. The lower ends of the front side rails are partly turned or twisted and are provided with soft rubber feet 47 attached thereto by means of rivets 48. These soft rubber feet enable the stand to be 20 mounted upon a show case or counter without injury to the show case or counter.

The lower original package or article to be displayed 38 indicated in dotted line in Fig. 1 rests at its front edge upon and against the 25 channel section of the cross member 27. At the rear end the lower original package 38 is supported upon the cross rod 44. The upper original package 38 is supported at its front edge upon the channel cross member 35, and at its rear upon the cross bar 20.

The apparatus herein shown and described is capable of considerable modification within the scope of the claims without departing from the spirit of my invention.

35. What I claim is:

1. A display stand comprising a relatively long front frame having a short section near its upper end bent to an obtuse angle relative to the main section of said front frame and 40 a plate spanning the lower front of said front frame, and adapted to display advertising matter, said front frame being composed of front side rails and a plurality of channelled cross bars serving to space apart the front 45 side rails and to form supports for the front of the bottoms and front ends of the downwardly inclined articles to be displayed, a relatively short rear frame pivotally attached at its upper end to the upper end of 50 said front frame and composed of rear side rails and cross rods serving to space apart

said rear side rails, front brace links and rear brace links respectively pivotally connected together near one end thereof upon a cross-bar and respectively pivotally attached 55 at their opposite ends to intermediate positions on said front side rails and rear side rails, said brace rods serving when in their extended positions to rigidly support the front frame and rear frame relatively in their extended position and when folded one upon the other to permit said front and rear frames to assume a collapsed position side by side and substantially parallel one to the other, and means carried by said frames to support the rear ends of the articles to be displayed independently of the support for the front end of said articles to be displayed. 60

2. A display stand comprising a relatively long front frame having a short section at its upper end bent to an obtuse angle relative to the main section of said front frame, said front frame being composed of front side rails and a plurality of channelled cross bars 70 serving to space apart the front side rails and to form supports for the bottoms and front ends of the downwardly inclined articles to be displayed, a relatively short rear frame pivotally attached at its upper end to the upper bent end of said front frame and composed of rear side rails and upper and lower cross-rods serving to space apart said 75 rear side rails, front brace links and rear brace links respectively pivotally connected together at the meeting ends thereof and 80 respectively attached at their opposite ends to intermediate positions on said front side rails and said rear side rails, said brace rods serving when in their extended positions to rigidly support the front frame and rear frame relatively in their extended position and when folded one upon the other to permit said front and rear frames to assume a collapsed position side by side and substantially parallel one to the other, said rear 85 cross-rods serving to support the rear ends of the articles to be displayed independently of the channelled supports for the front ends of the articles to be displayed. 90

In testimony whereof I have affixed my 100 signature.

EDWARD BRUNHOFF.
